(57) **CLAIM**

The ornamental design for a traction-decompression table, as shown and described.

DESCRIPTION

FIG. 1 is a perspective view of my ornamental design; FIG. 2 is a left elevational view of the ornamental design of FIG. 1; FIG. 3 is a right elevational view of the ornamental design of FIG. 1; FIG. 4 is a front elevational view of the ornamental design of FIG. 1; FIG. 5 is a rear elevational view of the ornamental design of FIG. 1; FIG. 6 is a top plan view of the ornamental design of FIG. 1; and,

FIG. 7 is a bottom plan view of the ornamental design of FIG. 1.

The broken lines showing of the traction-decompression table is included for the purpose of illustrating portions of the traction-decompression table and forms no part of the claimed design.
